ARCH P. RIDENOUR, OF LOS ANGELES, CALIFORNIA

BATTERY TERMINAL AND LINER PULLER

Application filed June 20, 1928. Serial No. 286,828.

This invention relates to pulling devices of the type employed for pulling wheels from their associated shafts and liners from the structure in which they are mounted, and 5 has for an object the provision of an improved type of puller provided with means operable to clamp gripping jaws rigidly onto the article to be removed from its supporting structure, to insure the firm gripping of the 10 article during the pulling process.

The embodiment herein described finds a particular field of utility in pulling terminal clamps of storage batteries from their associated terminal posts, since this embodiment 15 is relatively small and adapted for doing relatively light work only. I wish it to be understood, however, that the invention contemplates producing the device in enlarged form composed of heavier members so that 20 heavier work can be accomplished thereby. Accordingly, in the following description of the device it should be understood that the word "terminal" is used in a descriptive and not a limiting sense, as the invention may be 25 employed for pulling other devices than battery terminal clamps.

A more detailed object is the provision of a battery terminal clamp puller wherein the gripping jaws are pivotally mounted upon 30 the frame of the puller and wherein means are provided for mechanically forcing the gripping jaws to gripping position, this means comprising the conical surface of an operating head which is threaded in to the 35 frame of the puller with the jaws operatively engaged with the conical surface in such a manner that as the head is advanced by means of its threaded connection in respect to the frame, the jaws are positively forced 40 to gripping position.

It is a further object of the invention to provide a device of this general character which will be relatively simple and inexpensive in construction and which will be 45 generally superior in efficiency and serviceability.

The invention possesses other objects and features of advantage, some of which, with the foregoing, will be set forth in the following description of the preferred form of my

invention which is illustrated in the drawings accompanying and forming a part of the specification. It is to be understood that I do not limit myself to the showing made by the said drawings and description, as I may 55 adopt variations of the preferred form of my invention as set forth in the claims.

Referring to the drawings,

Figure 1 is a side elevation of the puller of my invention and a portion of a storage 60 battery, the puller being shown in position to pull one of the terminal clamps of the battery from its associated terminal post;

Fig. 2 is a top plan view;

Fig. 3 is a horizontal sectional view taken 65 upon the line 3—3 of Figure 1 with the direction of view indicated by the arrows;

Fig. 4 is a horizontal sectional view taken upon the line 4—4 of Figure 1 with the direction of view indicated by the arrows; 70

Fig. 5 is a horizontal sectional view, the plane of section being indicated by the line 5—5 of Figure 1 and the direction of view indicated by the arrows;

In terms of broad inclusion, the pulling device of my invention comprises a frame having a pulling shaft threaded therethrough and a jaw operating head threaded thereupon. A pair of jaws are pivoted to the frame in such position that they are 80 in operative engagement with a conical surface which is provided upon said operating head whereby the jaws may be positively moved to gripping position and there retained by moving the operating head in respect to the frame. 85

Specifically describing the present embodiment, my invention comprises a frame composed of a pair of spaced parallel arms 6 and 7. An operating head 8 has a cylindrical extension 9 provided with threads 11 by means of which a threaded engagement between the operating head 8 and the upper arm 6 is established, it being understood that the portion 9 of the head 8 is threaded through 95 the upper arm 6 midway between the ends thereof.

The head 8 is provided with an axial bore 12 within which a push rod 13 is journaled adjacent its upper end 14. The other end of 100

the push rod 13 is provided with threads 16 by means of which a threaded engagement with the lower arm 7 of the frame is established. A pushing head 17 is swiveled to the lower end of the push rod 13.

5 A pair of levers 18 are provided, each being pivoted by a pin 19 to one end of the lower arm 7 and each having a guide pin 21 rigid therewith adjacent its upper end. The pins 21 are slidable radially in respect to the push rod 13 in slots 22 in the upper arm 6. Thus, means are provided which substantially prevent relative movement between the upper and lower arms 6 and 7 but which permit 10 levers 18 to swing about their pivots 19 to vary the distance between the upper ends of the levers.

15 The lower ends of the levers 18 are bent inwards to provide gripping jaws 23 which, in the present embodiment, are provided with 20 concave arcuate surfaces 24 at their extremities corresponding in radius to the conventional terminal posts 26 of storage batteries 27 so that the jaws 23 may be positioned about 25 one of these posts and engaged beneath the associated terminal clamp 28.

25 Means for mechanically forcing the jaws 23 to gripping position are provided. The operating head 8 has a knurled flange 31 and a 30 conical surface 32 flaring downwards therefrom. The upper end of each of the levers 18 is bent inwards as at 33 to engage the conical surface 32 so that as the operating head is 35 threaded upwards from the upper arm 6 to which it is threaded, the conical surface 32 will wedge the upper ends 33 of the levers 18 apart. This results in moving the levers 18 about their respective pivots 19 forcing the gripping jaws 23 inwards.

40 A leaf spring 36 is attached to the lower arm 7 adjacent each of its ends and extends downwards therefrom to engage the adjacent lever 18 below its pivot 19. As a result the jaws 23 are normally urged outwards, retaining the upper ends 33 of the levers 18 45 against the conical surface 32.

The manner of operating my improved puller is substantially as follows:

45 The operating head 8 is first threaded downwards into the arm 6 to permit the upper ends 33 of the levers 18 to move together and separate the jaws 23 sufficiently to permit placing the jaws 23 under the terminal clamp 28 and upon opposite sides of the terminal post 26 of the battery 27 from which it is desired to remove the terminal clamp 28. Then by rotating the head 8 in that direction which will cause the head 8 to move upwards from the arm 6, the conical surface 32 may be made to 50 wedge the upper ends 33 of the levers 18 apart and force the gripping jaws 23 toward each other so as to establish a firm grip below the terminal clamp 28. Then the push rod 13 should be rotated so that its threads 16 cause 55 the push rod 13 to be advanced downwards

through the arms 6 and 7 constituting the frame of the device. In order to facilitate such rotation of the push rod 13 a handle 37 is provided at the upper end of the push rod. This rotation of the push rod 13 should be 60 continued until the pushing head 17 rests upon the top of the terminal 26. After this, further rotation of the push rod 13 will result in pulling the terminal clamp 28 from its terminal post 26.

75 I claim:

1. A puller comprising a two part frame, a push rod threaded therein, a plurality of levers pivoted intermediate their ends to one part of the frame and slidably engaged with the other part of the frame, a jaw at one end of each of said levers, a head threaded to that part of the frame in which the levers are slidable, there being a conical surface upon said head adapted to engage the other ends of said levers to move the levers about their pivots and to move the jaws to gripping position and means for rotating the push rod within the frame.

2. In a puller, a frame comprising a pair of spaced arms, a plurality of levers pivoted to one of said arms, a gripping jaw carried by each of said levers, a head threaded to the other of said arms, there being a conical surface upon the head adapted to engage said levers and turn them upon their pivots to force the jaws to gripping position.

3. In a puller, a frame comprising a pair of spaced arms, a plurality of levers pivoted to one of said arms, a gripping jaw carried by each of said levers, a head threaded to the other of said arms, there being a conical surface upon the head adapted to engage said levers and turn them upon their pivots to force the jaws laterally of the frame to gripping position, and a push rod movable longitudinally of the frame.

4. In a puller, a frame comprising a pair of spaced parallel arms, a head threaded through the upper of said arms, a push rod journaled in said head to extend through the associated arm and threaded through the lower arm, a pair of levers pivoted to said lower arm, gripping jaws carried by the lower ends of said levers, and means limiting the movement of the upper ends of the arms to movement radially of the associated arm, there being a conical surface on said head adapted to engage the upper ends of the levers and turn the levers upon their pivots to force the jaws to gripping position.

5. In a puller, a frame comprising a pair of spaced arms, a head threaded through the upper of said arms, a push rod journaled in said head to extend through the associated arm and threaded through the lower arm, a pair of levers pivoted to said lower arm, gripping jaws carried by the lower ends of said levers, and pins rigid with the levers adjacent their upper ends and slidably radially

of the push rod in slots in the upper arm, there being a conical surface on said head adapted to engage the upper ends of the levers and turn the levers upon their pivots to force the jaws to gripping position.

5 6. In a puller, a frame comprising a pair of spaced arms, a head threaded through the upper of said arms, a push rod journaled in said head to extend through the associated 10 arm and threaded through the lower arm, a pushing head swiveled to the lower end of said push rod, a pair of levers pivoted to said lower arm, the lower ends of said levers being bent inwards to form gripping jaws, and 15 pins rigid with the levers adjacent their upper ends and slidable radially of the push rod in slots in the upper arm, there being a conical surface flaring downwards from said head, the upper ends of said levers engaging 20 said conical surface so as to be separated thereby when the head is threaded outwards from the associated arm.

7. In a puller, a frame, opposed levers pivoted thereto, a gripping jaw carried by each 25 of said levers, a flaring head carried by said frame with said levers engaging the flaring surface thereof, means for advancing said head in respect to said frame, and levers to force a different part of the flaring portion 30 thereof into engagement with said levers, and a push rod threadedly engaged with said frame in planar alignment with said jaws.

8. In a puller, a frame, opposed levers pivoted thereto, a gripping jaw carried by each 35 of said levers, a conical head carried by said frame with said levers engaging the conical surface thereof, means for advancing said head in respect to said frame and levers to force a different part of the conical portion 40 thereof into engagement with said levers, and a push rod threadedly engaged with said frame in planar alignment with said jaws.

In testimony whereof I have signed my name to this specification.

45 ARCH P. RIDENOUR.
